UNITED STATES PATENT OFFICE.

CHARLES DRESEL, OF BROOKLYN, NEW YORK.

TABLE ATTACHMENT FOR BEDS.

1,221,296.

Specification of Letters Patent.

Patented Apr. 3, 1917.

Application filed July 7, 1914. Serial No. 849,593.

To all whom it may concern:

Be it known that I, CHARLES DRESEL, a citizen of the United States, residing at Brooklyn, in the county of Kings, State of New York, have invented certain new and useful Improvements in Table Attachments for Beds; and I do hereby declare the following to be a full, clear, and exact description of the invention, such as will enable other skilled in the art to which it appertains to make and use the same.

This invention relates to improvements in bed attachments, and particularly to table attachments for beds.

15 The principal object of the invention is to provide a table attachment for a bed which can be readily folded and disposed under the bed out of the way, the device remaining attached to the side rail of the bed.

20 Another object is to provide a device of this character which is simple in construction and which will properly support a tray over a bed within convenient reach of the patient.

25 Other objects and advantages will be apparent from the following description, when taken in connection with the accompanying drawings.

In the drawings:

30 Figure 1 is a side elevation of a portion of a bed showing my invention applied thereto and in extended position.

Fig. 2 is a side elevation of the device, only a fragment of the bed being shown.

35 Fig. 3 is a view taken from the same direction as Fig. 2, but showing the device in folded position.

Fig. 4 is a vertical longitudinal sectional view through the device of Fig. 1.

40 Fig. 5 is a view taken from the same direction as Fig. 1 showing device in folded position.

Fig. 6 is an elevation of the device in extended position taken from the opposite side to that shown in Fig. 1.

Referring particularly to the accompanying drawings, 10 represents a recessed L-shaped member which is arranged to be engaged with a portion of the side rail of an iron bed. Disposed against the outside of the side rail is a standard 11 which carries a pair of set screws 12 which are arranged to draw the member 10 tightly into engagement with the rail. The upper end of the standard 11 is bifurcated and has pivotally

mounted therein the lower end of an inclined arm 13, the upper end of this arm being pivotally mounted within the bifurcation formed in the adjacent end of a leaf 14. The opposite end of this leaf is also 60 bifurcated and carries pivotally therein a member 15 on which is formed the table 16, this table being adapted to support a tray. Secured to the inner side of the standard 11 is an upwardly inclined arm 17 65 against which the arm 13 engages when the device is in extended position. The lower side of the inner end of the leaf 14 carries a block 18 against which the upper end of the arm 13 engages so that the said leaf will 70 be held in a horizontal position. Carried by the arm 17 and by the block 18 are set screws 19 which are arranged to be moved against the arm 13 so as to properly adjust the arm to bring the leaf 14 into a perfectly 75 horizontal position. Through the outer end portion of the leaf 14 is a set screw 20 which engages against the under face of the member 15 to properly level the table 16.

Thus when the device is in extended position, as clearly seen in Fig. 2, the table 16 will be disposed over the bed in proper position for the patient to reach the tray carried thereby. When the device is to be put out of use, the leaf 14 is swung over toward the arm 13 and then the arm 13 swung down against the outer face of the standard 11. This will cause the leaf 14 to swing under the bed, and to hold the leaf in this position against dropping to the floor, there is provided a spring hook or latch 21 on the lower end of the standard, this latch being engaged with the leaf 14 as clearly shown. When so folded the table 16 and member 15 may be swung so as to dispose the table 90 downwardly toward the floor.

It will be noted that the standard 11 remains attached to the rail of the bed, and to throw the device into operative position, it is only necessary to disengage the latch and 100 swing the parts up into the position of Fig. 2.

What is claimed is:

A table attachment for a bed comprising a rail clamping means including a standard, 105 an arm pivotally mounted in the upper end of the standard, adjustable means carried by the standard and engaging the arm for varying the inclination of the arm, a leaf pivotally carried by the upper end of the arm and 110

disposed normally in a horizontal position over the bed, adjustable means carried by the said leaf for engagement with the arm to vary the inclination of the leaf, a tray 5 supporting table carried by the other end of the leaf, said leaf and arm being arranged to be swung on their pivots to dispose the said leaf beneath the bed, and a resilient detent carried by the standard for supporting en-

gagement with the said leaf when the latter 10 is in its lowered position.

In testimony whereof, I affix my signature, in the presence of two witnesses.

CHARLES DRESEL.

Witnesses:

DANIEL J. HART,
DANIEL J. QUIGLEY.
